United States Patent Office

Des. 212,340
Patented Oct. 1, 1968

212,340

LEFT, CENTER AND RIGHT READING YARDSTICK

Charles E. Hull, 713 1st St., Westfield, N.J. 07090

Filed Oct. 10, 1967, Ser. No. 8,943

Term of patent 14 years

(Cl. D52—6)

FIG. 1

FIG. 2

FIG. 3

FIG. 4

FIG. 5

FIGURE 1 is a front elevational view of a left, center and right reading yardstick, showing my new design;

FIGURE 2 is a view taken from the opposite side thereof;

FIGURE 3 is a plan view thereof;

FIGURE 4 is a bottom plan view thereof; and

FIGURE 5 is an end elevational view thereof.

I claim:

The ornamental design for a left, center and right reading yardstick, substantially as shown.
